RUBBER FLOOR COVERING OR SIMILAR ARTICLE

Alan Brown, Higganum, Conn., assignor to The Buxbaum
Company, Canton, Ohio, a corporation of Ohio

Application December 21, 1955, Serial No. 39,413

Term of patent 3½ years

(Cl. D92—4)

FIG. 1

Fig. 1 is a plan view of a rubber floor covering, showing my new design; and

Fig. 2 is an enlarged fragmentary view of the floor covering shown in Fig. 1, illustrating a portion thereof at a 90° angle thereto.

The floor covering is of conventional thickness.

A unit is enclosed in broken lines in Fig. 1 of the drawings and is repeated as indicated.

I claim:

The ornamental design for a rubber floor covering or similar article, substantially as shown and described.
